UNITED STATES PATENT OFFICE.

JOHN McCART, OF NEW YORK, N. Y.

PISTON-HEAD FOR STEAM-ENGINES.

SPECIFICATION forming part of Letters Patent No. 357,777, dated February 15, 1887.

Application filed August 17, 1886. Serial No. 211,145. (No model.)

To all whom it may concern:

Be it known that I, JOHN McCART, of the city, county, and State of New York, have invented a new and Improved Piston-Head for 5 Steam-Engines, of which the following is a full, clear, and exact description.

My invention relates to a piston-head packed with split metallic rings; and the invention consists in the application of the steam-checks, 10 as hereinafter described and claimed.

Reference is to be had to the accompanying drawings, forming a part of this specification, in which similar letters of reference indicate corresponding parts in all the figures.

15 Figure 1 is a side view of my new and improved piston-head. Fig. 2 is a sectional elevation of the same. Fig. 3 is a sectional view taken on the line $x-x$ of Fig. 1. Fig. 4 is a plan view of one of the split packing-rings with its 20 spring. Fig. 5 is a perspective view of the corrugated spring for spreading the packing-rings. Fig. 6 is a detailed plan view of a part of one of the packing-rings, showing the arrangement of the steam-check at the split or 25 opening in the ring. Fig. 7 is a sectional elevation of the same on the line $y-y$ of Fig. 6. Fig. 8 is an enlarged sectional elevation of the two packing-rings with the corrugated spreading-spring removed, and Fig. 9 is a similar 30 view showing the said corrugated spreading-spring in place.

In constructing my improved piston-head I employ two split packing-rings, $\mathbf{A A}$, of metal. These are placed upon the body B , formed 35 with the flange C , which latter is of an appreciable less diameter than the bore of the cylinder with which the piston-head is to be used, and the body B is secured upon the piston-rod F in an ordinary manner, and the rings are 40 held in place upon the body B by the annular disk D and the bolts $E E$, which pass through the disk and screw into screw-tapped openings i made in the body A . The annular disk D is of the same external diameter as the flange 45 C , and the adjacent surfaces of the disk D and flange C are faced off, as shown at $i' i'$, to form flat and true seats for the outer edges of two packing-rings, $\mathbf{A A}$, which edges are also made true, to form steam-tight joints with the said 50 seats $i' i'$, as hereinafter described.

The body B , between the screw-threaded openings i , is recessed, as shown at i^2 , to reduce the weight of the body B , and opposite each of the said screw-threaded openings i a projection or lug, i^3 , is formed to strengthen 55 the body B at the points where the bolts E enter it, while between these lugs or projections i^3 the metal is removed, as shown at i^4 , to still further lessen the weight of the body and relieve it of surplus and useless metal. 60

The packing-rings $\mathbf{A A}$ are duplicates of each other, each being split diagonally at a , and are constructed to form a recess, a' , in its outer edge opposite the opening or split a , to receive a small block, d , to serve as a steam-check to prevent steam from entering the piston-head at the slit or opening a . A small lip, d' , (shown clearly in Figs. 6 and 7,) is formed upon each steam-check d , and a corresponding recess or depression, d^2 , is formed in the recess a' , to receive the lip d' , for holding the steam-check in place, and the steam-checks are of slightly less length than recesses a' , so the said checks will permit longitudinal movement of the parts due to opening and closing of the 75 split rings.

Upon the inner surfaces of the packing-rings $\mathbf{A A}$ are formed the lugs or bars b , and a circular spring, G , is fitted within each ring, which acts to expand the ring. The springs G are 80 endless, or "ring-springs," and are corrugated in such a manner as to bear upon the lugs or bars b , and also upon the inner surface of the rings between the lugs or ribs, as shown in Fig. 4, so that the springs may be readily introduced into the rings, and so that the outward or opening pressure of the springs will be equal at all parts of the packing-rings. 85

Between the two packing-rings $\mathbf{A A}$ is placed the corrugated spring H , the corrugations or waves of which form opposite small curved springs, which are compressed when the bolts $E E$ are tightly screwed down, so that these small curved springs act constantly to spread the packing-rings $\mathbf{A A}$ apart, which results in 95 forcing the outer flat surfaces of the said rings against the flat seats $i' i'$ of the flange C and disk D , thus forming steam-tight joints between the packing-rings and the adjoining surfaces of the said flange and disk, so that no 100

steam can enter the piston-head between the packing-rings and their confining surfaces or plates.

The adjacent surfaces of the packing-rings 5 are reduced or slightly cut away, as shown at *e e*, Figs. 8 and 9, to form a space for the interposed corrugated spring *H*, and to form the outer surrounding lips, *e' e'*, to confine the corrugated spring *H*.

Having thus described my invention, what I claim as new, and desire to secure by Letters Patent, is—

The ring *A*, slotted at *a*, and formed at the slot upon the inside, with the recess *a'*, lip *d'*, and depression *d*², in combination with the steam-check *d*, of less length than the recess *a'*, and grooved to fit over the lip *d'*, substantially as described.

JOHN McCART.
